MOUTH ORGAN

Hans Bibus, Kusnacht-Zurich, Switzerland

Application September 25, 1946, Serial No. 699,153
In Switzerland July 2, 1946

5 Claims. (Cl. 84—377)

1

In most of the mouth organs in use today the major and minor scales are divided into two groups, the first being played on air being exhaled and the second on air being inhaled. For example, on exhaling, an instrument tuned to the key of C major will sound the single notes C, E, G, C, E, G, C, or, if all are blown together, the C major chord. On inhaling, the remaining notes of the scale of C major, G, B, D, F, A, B, D, are sounded giving the chord of G major in the lower tone range and a disharmonic chord in the upper tone range both of which are mostly used to replace a G seventh. Playing on diatonic instruments as mentioned above is therefore restricted to two chords.

Chromatic slide valve mouth organs increase musical possibilities by incorporating semi-tones. These chromatic mouth organs are tuned in principle in exactly the same way as the diatonic mouth organs previously described. The former, however, incorporate two reed plates, the reeds of one plate being tuned half a tone higher than those of the other. When playing, one or the other of the reed plates can be selected by operating the slide-valve. In this way all 12 notes of the chromatic scale can be played, as well as four chords, whose application, however, is limited, with the result that this instrument is chiefly suited for playing the melody only.

Other designs are known which enable several chords in different keys to be played. These instruments are very complicated and demand great skill on the part of the person playing them, with the result that these mouth organs are not very popular.

The present invention relates to a mouth organ in which keys and chords are not determined or rather are determined not only by the direction of the flow of air but by the position of perforated slide-valves which are interposed in the air path. Contrary to most of the mouth organs in use hitherto, in the case of this instrument melody and accompaniment chords are not selected simultaneously. By moving the slide-valves different chords can be combined with the same melody note. In this connection it is very important that at least two sliding plates, which can be moved separately, should be fitted one behind the other and their perforations arranged in such a way that in the various positions of the slide-valves air channels are opened which correspond to the various chords which can be made with the reeds of the instrument. The number of slide-valves depends both on the number of chords which are to be available and on the number of

2

different positions which each single slide valve can take up. The fewer the number of slide-valve positions the greater the number of slide valves which have to be incorporated to obtain a given number of chords.

The accompanying drawings represent a constructional example of a mouth organ in accordance with the present invention. The example shown is a C major tonic instrument with three slide valves by means of which the chords, C major, G seventh, A minor, D minor, E minor and F major sixth can be played. These are the chords most frequently met with in the simpler C major compositions. In addition to these a whole series of disharmonic chords can be formed which are useful for transitional purposes.

Fig. 1 is a view of a mouth organ in perspective, with the various sliding plates drawn out in order to make their underlying principle more easily understood.

Fig. 2 is a cross-section through line I—I in Fig. 3.

Fig. 3 is a cross-section through line II—II in Fig. 2.

25 Figs. 4—9 show diagrammatically the various positions of the sliding plates.

Fig. 10 shows the special perforation of the various sliding plates.

Fig. 11 is a cross-section through line III—III in Fig. 12.

Fig. 12 is a cross-section through line V—V in Fig. 11.

Fig. 13 is a cross-section through line IV—IV in Fig. 11.

35 Fig. 14 is a side-view of the mouth piece as in Fig. 12.

Figs. 1—3 illustrate the general design of the instrument.

In the reed bank 1 of the instrument are cut 40 the upper and lower reed chambers 2, 3 which are covered on top and underneath by reed plates 4, 5 containing all the notes of the scale of C. Slots 6 cut in the reed bank act as guides for slide valve bows 7, 8, 9 which can be moved backwards and forwards in the said slots. The slide valve bows 7, 8, 9 support and stretch the slide valves 11, 12, 13 in such a way that by means 45 of these bows 7, 8, 9 the slide valves 11, 12, 13 can be moved between cover plate 10 in front of the reed bank and mouth piece 14 without danger of bending. The displacement of slide valve bows 7, 8, 9 and thus of slide valves 11, 12, 13 is obtained by exerting pressure on double-armed levers 16, 17 supported by spindle 15. These double-armed 50 levers are designed and supported in such a way

that one of the outside levers, two adjacent levers, or all three levers together can be depressed easily with one finger.

Reed bank 1 incorporates springs 21 which actuate bows 7, 8, 9 and thus slide valves 11, 12, 13. On releasing levers 16, 17 both bows and valves are brought back to their medial position. 22 is the metal cover plate of the mouth organ.

Figs. 4-9 show how the chords C major, G seventh, A minor, D minor, E minor and F major sixth can be formed by bringing the perforated slide valves into the various positions. The constructional example shown in the drawings is, of course, only one of numerous possible alternatives. If the perforated slide valves are designed so that they can be moved into five different positions instead of three, the chords mentioned above can be obtained by incorporating only two perforated slide valves instead of three without otherwise altering the instrument.

The mouth organ so far described in the constructional example has the disadvantage that for every note of a melody a chord must be selected in which the note occurs. This is also the case even when complete chords are not desired and to this end the open channels between the octave of the notes of the melody are covered with the tongue. This difficulty can be overcome as shown for example in Fig. 10 by means of a mouthpiece 23 capable of sliding along the mouthpiece guide 14' and by supplementing all perforated slide valves, the cover plate and the mouthpiece guide with a series of holes for the notes of the melody.

In Fig. 10 the perforated slide valves, modified as above, are numbered 11', 12' and 13', while the cover plate is numbered 10'.

As Figs. 11-14 show, this mouthpiece incorporates an upper channel 24 which operates the perforations of the chord series and a lower channel 25 which operates the perforations of the melody series. Channel 25 leads into two air exits which are spaced one octave from each other, while channel 24 leads to a slot between the two. The air inlets to channels 24, 25 are separate and can therefore be covered with the tongue. The embodiment of the mouthpiece shown here is also only given as an example because the openings can be spread out to cover more than one octave. In addition, with the mouthpiece shown it is possible to combine any chord which can be played on the instrument with each single note of the tonic series, which is of vital importance if proper harmony is to be obtained. Furthermore, this mouthpiece enables the player to alternate between melody and accompaniment.

It will be noted that in each slide one or two openings are omitted in each octave length and that each such unperforated area covers an open-

ing of another slide in the medial position of the slides.

As indicated previously, the mouth organ constructed in accordance with the present invention can obviously be designed to play semi-tones in order to increase the musical scope of the instrument. The only changes necessary are in the number of sliding plates, their several positions and the perforation arrangement.

10 The mouth organ constructed in accordance with the present invention is very simple, can be manufactured cheaply and satisfies the demand for an instrument capable of producing correct harmony, at the same time being easy to learn.

15 I claim:

1. A mouth organ comprising a reed bank having a perforated cover plate, a mouthpiece fixed to the reed bank, at least two independently movable slides arranged between the reed bank and

20 mouthpiece, said slides having perforations distributed corresponding to the exhaling openings of the mouth piece and to the cover plate of the reed bank, at least one and no more than two openings per octave length being omitted in each 25 slide in such manner that in the medial position of all of the slides each area of omission of a slide covers an opening of another slide.

2. A mouth organ according to claim 1, wherein the number of slide valves is three.

3. A mouth organ according to claim 1, including bows for supporting the slide valves and levers for shifting the bows in opposite directions.

4. A mouth organ according to claim 1, including bows for supporting the slide valves and movable in opposite directions, and springs resisting the movement of the bows and acting, on release of a shifted bow, to return the same to medial position.

5. A mouth organ according to claim 1, including a mouthpiece slidable over the whole length of the air inlet, said mouthpiece being provided with two channels, one of which acts on two notes separated by an octave, while the other leads, via a slot, to the other notes or air inlets which are 45 covered by the mouthpiece.

HANS BIBUS.
